SIGNALING ARRANGEMENT FOR
TELEGRAPH SYSTEMS

Robert James Egner, Ridgewood, and Charles Robert Walker, Jersey City, N. J., assignors to American Telephone and Telegraph Company, a corporation of New York

Application December 5, 1941, Serial No. 421,718

6 Claims. (Cl. 178—69)

This invention relates to telegraph and teletypewriter systems. More particularly, this invention relates to telegraph and teletypewriter systems in which a subscriber connected to the system may be notified this his circuit has been switched into the system so that he may transmit signals thereover.

In telegraph systems where the subscriber's station is connected to a central office or central switching point by a line circuit which may be of the open-wire type, voltages induced from power sources and other extraneous sources may become so large as to interfere with signaling over the line circuit. In order to overcome such interference, a separate circuit or conductor, known as a neutralizing circuit or conductor, may be added to the system for the purpose of neutralizing such interfering voltages. In cases where it is desired to notify any particular subscriber that he is connected to another distant subscriber through the central office or switching point and to keep the subscriber notified continuously that he is so connected, it has heretofore been necessary to provide still a third circuit or conductor over which such auxiliary signals may be transmitted without in any way interfering with signaling over the line circuit. The addition of this third conductor or circuit is, of course, costly and would add to the maintenance.

According to the present invention it is proposed to obviate the requirement for any such third conductor or circuit by utilizing the neutralizing conductor for auxiliary signaling to the subscriber, thereby indicating to the subscriber that he has or has not been connected to the system and that his signals are or are not being received over the system.

Another object of this invention is to connect a subscriber's station to a central office or other switching point by two conductors, (1) a line conductor over which signals may be transmitted and (2) a neutralizing conductor running parallel thereto to substantially reduce the effect of extraneous voltages, and to employ the neutralizing conductor for auxiliary signaling to the subscriber's station.

These and other objects of this invention will be better understood from the detailed description hereinafter following, when read in connection with the accompanying drawing showing one embodiment of the invention merely for the purpose of illustration.

Referring to the drawing, there is shown a subscriber's office at the extreme left at which there is located a sending relay R_1 and a receiv-

ing relay R_2 . The receiving relay R_2 includes four windings W_1 , W_2 , W_3 and W_4 , which are all approximately of the same number of turns. The winding W_1 is connected between the armature of the sending relay R_1 and the line circuit or conductor L_1 —which may be an open wire line of well-known type—extending between the subscriber's office and a central office or switching point. The winding W_2 is connected between the lower terminal of the winding W_1 and the grounded artificial line AL_1 , the artificial line AL_1 being employed in a well-known manner to balance the main line conductor or circuit L_1 . A neutralizing conductor or circuit L_2 is connected to the winding W_3 of the receiving relay R_2 while the artificial line AL_2 is similarly connected through the winding W_4 of relay R_2 to the lower terminal of its winding W_3 . The artificial line AL_2 is similar to the artificial line AL_1 and is employed to ensure that the neutralizing path has the same impedance as the transmission path.

At the central office the line circuit L_1 is connected to the armature of a relay R_3 through the winding W_5 of a relay R_4 . The artificial line AL_3 is connected to the winding W_6 of relay R_4 for the purpose of balancing the line L_1 at the central office. The relay R_4 also includes windings W_7 and W_8 which are similar to windings W_5 and W_6 , respectively, and a biasing winding W_9 .

In the idle condition of the system the neutralizing wire L_2 is connected to the battery B_1 at the central office by a circuit extending through the contact K_1 of the relay R_5 . This neutralizing wire is associated with a balancing network AL_4 which is similar to network AL_3 at the central office to keep the impedance of the neutralizing path equal to that of the transmission path. In the idle condition of the system, also, the upper winding of the relay R_3 is connected to the battery B_1 through the make-before-break contacts K_2 associated with the upper armature of relay R_5 . But during signaling over the system, the relay R_5 is operated and therefore the upper winding of the relay R_3 is connected to the upper windings of relays R_6 and R_7 over a circuit which includes the upper armature and make contact of relay R_5 , the innermost lower armature and make contact of relay R_5 and the operating circuit of selector NTS. The lower winding of the relay R_3 is connected to an artificial line AL_5 for balancing purposes.

The selector NTS may be, for example, a non-typing teletypewriter or selector of well-known construction. In response to a teletypewriter character such as "Figures" it will close its con-

tact K_5 , then in response to a subsequent teletypewriter character such as upper case "B," it will close its contact K_3 momentarily, and later, in response to a third teletypewriter character such as upper case "D," it will likewise close its contact K_4 momentarily.

The lower windings of the relays R_6 and R_7 are also connected to an artificial line AL_6 . The apex of the upper and lower windings of relay R_7 is connected to the armature of the relay R_8 . The midpoint of the upper winding of relay R_8 is connected to the armature of relay R_6 while the midpoint of the lower winding of relay R_8 is connected to the armature of the relay R_7 . The two windings of relay R_8 are connected to a metallic telegraph line or circuit L_3 which may extend to any one of several distant subscribers or offices (not shown), the line L_3 being balanced by a network BN . The selector NTS, when closing its contacts K_5 in response to the receipt from line L_3 of the teletypewriter character "Figures" will remain closed thereafter until the receipt of a "Letters" signal as hereinafter described. The receipt of the teletypewriter character "B" from line L_3 will close the contact K_3 for the purpose of operating the relay R_5 , as will be pointed out hereinafter. The closure of the contacts K_4 in response to the teletypewriter character "D" will operate the relay R_9 , as will be described hereinafter. The operations of relays R_5 and R_9 will therefore be controlled by contacts K_3 and K_4 of selector NTS but the ground for the operating circuits of these relays will be obtained through the contact K_5 of the selector. The subsequent receipt of the teletypewriter character "Letters" from line L_3 will restore the selector NTS to its normal position, thereby opening the contact K_5 . The closing of the contacts K_3 or K_4 will be ineffective unless the appropriate signal has previously been received to close the selector contact K_5 .

One of the features of the arrangement of this invention is the inclusion at the subscriber's office of the relay R_{10} in series with the neutralizing conductor L_2 . A lamp and battery may be connected in series with the armature and either the front or back contact of relay R_{10} so that the lamp will be lighted either when the relay R_{10} is energized or when it is deenergized as desired. If desired two lamps P_1 and P_2 which may be of different colors may be provided as shown in the drawing, one lamp P_1 being connected to the front contact and the other P_2 connected to the back contact of relay R_{10} . To obtain a balanced condition in the line and neutralizing conductors L_1 and L_2 a similar relay arrangement R_{11} or an equivalent network, is positioned in series with the line conductor L_1 . The latter device, however, need not be a relay but may be any type of network which has the same impedance characteristics as the relay R_{10} .

As will be explained hereinafter the system is so arranged that when the subscriber's office is connected through at the central office to line L_3 , relay R_{10} will be released and a suitable visual indication will be obtained from the lamp P_2 . The neutralizing conductor L_2 is connected through contacts K_6 of relay R_5 to the grounded winding W_7 of relay R_4 when relay R_5 is operated. In that case relay R_{10} is released because battery B_1 is disconnected therefrom at contact K_1 of relay R_5 .

Thus when the subscriber receives an appropriate signal through the medium of lamp P_2 , it

will indicate that the line L_1 is connected to the line L_3 , thereby enabling him to transmit signals to or receive signals from line L_3 . When this happens the relay R_5 will be operated so as to open the contact K_1 of relay R_5 and then close the contact K_6 of relay R_5 so as to connect the neutralizing conductor L_2 to winding W_7 of relay R_4 . This will cause the release of the relay R_{10} at the subscriber's office. The lamp P_2 , after being illuminated, will remain illuminated and indicate that the subscriber's set and the circuit connected to line L_3 remain properly coupled together so that signals may be transmitted in both directions over the interconnecting circuits.

When a teletypewriter character such as "Figures" is received over the line L_3 , it will be relayed through relay R_8 and relays R_7 and R_6 to the selector NTS, which is connected to positive battery B_2 through the make-before-break contacts K_7 of relay R_5 . The receipt of this character will close the platen contact K_5 as already explained. The subsequent receipt of another character such as "B" over line L_3 will cause selector NTS to momentarily close its contacts K_3 , whereupon the relay R_5 will be operated over a circuit which includes contacts K_5 and K_3 of selector NTS, the winding of relay R_5 , battery B_2 and ground. The relay R_5 will be locked in its operated position through the back contact of the upper armature of relay R_8 , the locking circuit including battery B_2 , the winding of relay R_5 , the contacts K_8 of relay R_5 , the upper armature and back contact of relay R_9 and ground.

By operating relay R_5 in response to the receipt of a predetermined character over the line L_3 , the battery B_1 —which was previously connected through the make-before-break contacts K_2 of relay R_5 to the upper winding of relay R_3 —will be disconnected and the upper winding of relay R_3 will be connected to the upper winding of relay R_6 over a circuit previously noted. Moreover, the operation of relay R_5 will cause the closure of its contacts K_6 so as to connect the winding W_7 of relay R_4 to the neutralizing conductor L_2 . This will be accompanied by the release of the relay R_{10} at the subscriber's office, the extinction of lamp P_1 and the illumination of lamp P_2 . The illumination of lamp P_2 will indicate that the connection between line L_3 and the subscriber's office has been completed. Signals may then be transmitted between the station connected to the line L_3 (not shown) and the subscriber's office over the line circuit L_1 in both directions. The neutralizing conductor L_2 will at the same time function to substantially reduce, if not entirely overcome, the effects of power voltages and other extraneous voltages which may be induced into the exposed conductors L_1 and L_2 . The neutralizing conductor L_2 will therefore perform two functions, (1) as a neutralizing conductor to eliminate extraneous voltages and (2) as a medium for indicating to the subscriber through lamp P_2 that his circuit is connected through the central office equipment to another subscriber's station (not shown) for signaling in the usual way.

The closure of the contacts K_3 of the selector NTS is but momentary, as already indicated, in response to the receipt of the teletypewriter character "B." If at some later time the teletypewriter character "D" is received over the circuit L_3 , the selector NTS will close its contacts K_4 so as to operate the relay R_9 provided contact K_5 has been previously closed. The operating circuit for relay R_9 includes the battery B_2 , the

winding of relay R_9 , the contacts K_4 and K_5 of the selector NTS, and ground. The relay R_9 will thereafter be locked in its operated position through the contacts K_9 of relay R_5 , the locking circuit including battery B_2 , the winding of relay R_9 , the lower armature and make contact of relay R_9 , the contacts K_9 of relay R_5 , and ground. The operation of relay R_9 will also break the locking circuit of relay R_5 by opening the back contact of the upper armature of relay R_9 and the relay R_5 will then release. The release of relay R_9 will in turn bring about the release of relay R_5 because the contacts K_9 of relay R_5 will be opened. Thus upon the receipt of another teletypewriter character such as upper case "D," the relay R_9 will be operated and then both relay R_5 and relay R_9 will shortly thereafter be released.

Upon the release of relay R_5 the line L_3 will then be disconnected from the line L_1 and from the subscriber's office connected thereto. The upper winding of relay R_3 will then be reconnected to the battery B_1 through the make-before-break contact K_2 of relay R_5 . The winding W_7 of relay R_4 will also be disconnected from the neutralizing conductor L_2 by the opening of contacts K_8 of relay R_5 . The battery B_1 will be reconnected through contact K_1 of relay R_5 to the neutralizing conductor L_2 , whereupon the relay R_{10} will be re-operated to illuminate the lamp P_1 at the subscriber's office.

It will be apparent that any marking and spacing signals received over line L_3 after relay R_5 has been operated will move the armature of relay R_3 between its marking and spacing contacts M and S to alternately connect the oppositely poled batteries B_1 and B_2 to the apex of the windings of relay R_7 . These oppositely poled batteries will then be connected through the upper windings of the relays R_6 and R_7 , through the operating circuit of the selector NTS (not shown) and over the lower innermost armature and make contact of relay R_5 to the upper winding of relay R_3 . The armature of relay R_3 will be moved between its marking and spacing contacts in accordance with the signals received from line L_3 and connect corresponding oppositely poled batteries to the line L_1 through the winding W_5 of relay R_4 . These oppositely poled voltages will in turn energize the winding W_1 of relay R_2 so that the armature of relay R_2 will register these marking and spacing signals in a well known manner. During such signaling operations the neutralizing conductor L_2 will function to eliminate extraneous voltages.

In order to send signals from the subscriber's office over the lines L_1 and L_3 , the sending relay R_1 will be operated in accordance with marking and spacing signals. The armature of relay R_1 will connect ground to the line L_1 through the winding W_1 of relay R_2 for a marking signal and the positive battery B_4 to the main line L_1 through the same winding of relay R_2 for a spacing signal. These marking and spacing signals will then cause currents to flow through the winding W_5 of relay R_4 in opposite directions so as to move the armature of relay R_4 between its marking and spacing contacts M and S . As the armature of relay R_4 closes its contacts M and S it will alternately connect oppositely poled batteries to the apex of the windings of relay R_4 and thereby transmit oppositely poled currents to the upper windings of relays R_6 and R_7 . The interconnecting circuit includes the upper winding of relay R_3 , the upper armature and make contact of

5 relay R_5 , the lower innermost armature and make contact of relay R_5 , the operating circuit of the selector NTS (not shown) and the upper windings of relays R_6 and R_7 which are connected to the armature of relay R_8 and its marking contact M . The relays R_6 and R_7 will move their armatures between their marking and spacing contacts M and S in accordance with the signals transmitted from the subscriber's office and thereby connect oppositely poled batteries to the midpoints of the windings of the relay R_8 . These oppositely poled batteries will cause oppositely directed currents to flow over the line L_3 to the distant subscriber's station or central office (not shown).

10 During signaling from the subscriber's office to the circuit connected to the line L_3 the neutralizing wire L_2 will again perform its neutralizing functions to eliminate the effects of transient and extraneous voltages and the lamp P_2 will indicate to the subscriber that his circuit is connected to the line L_3 and that the subscriber's circuit is not transmitting signals "into the air." This is an important feature of this arrangement not only because it indicates that the subscriber's office and the line L_3 are interconnected but also because the indication is continuous and is interrupted only when the interconnecting circuit is broken.

15 20 25 30 While this invention has been shown and described in certain particular arrangements merely for the purpose of illustration, it will be understood that the general principles of this invention may be applied to other and widely varied organizations without departing from the spirit of the invention and the scope of the appended claims.

What is claimed is:

1. In a telegraph system, the combination of 40 a subscriber's station, a central office, a telegraph line over which telegraph signals may be transmitted, a neutralizing line which together with the telegraph line are interposed between the subscriber's station and the central office, the neutralizing line picking up extraneous voltages similar to those picked up by the telegraph line, means coupled to said lines whereby said extraneous voltages may be effectively nullified, a relay at the subscriber's office, the winding of said relay being connected to the neutralizing line, an indicating device controlled by said relay, and means at the central office for applying voltages to said neutralizing line to energize said relay.

55 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870

3. In a telegraph system, the combination of first and second stations, a line over which telegraph signals may be transmitted, a neutralizing wire, said neutralizing wire and said line running parallel to each other between said two stations, means connected to said line and said wire for the neutralization of extraneous voltages, a re-

lay at the first station having its winding connected in series with said neutralizing wire, a device at said first station having an impedance substantially equal to that of said relay winding and connected in series with said line, an indicating device controlled by said relay, and means at said second station for applying voltage to said neutralizing wire to operate said relay.

4. In a telegraph system, a first subscriber's station, a central office, a second subscriber's station connected to said central office, a telegraph line over which telegraph signals may be transmitted, an auxiliary line running parallel to said telegraph line, said telegraph line and said auxiliary line interconnecting the first subscriber's station and said central office, means connected to said lines for the neutralization of extraneous voltages, a relay at said first subscriber's station having its winding in series with said auxiliary line, an indicating device controlled by said relay, and means responsive to a predetermined signal from said second subscriber's station to indicate at the first subscriber's station whether or not the two subscribers' stations may send telegraph signals to each other over the telegraph line, said means including apparatus at the central office responsive to said predetermined signal to apply voltage to said auxiliary line to operate said relay.

5. In a telegraph system, the combination of first and second stations, a telegraph line over which telegraph signals may be transmitted, a neutralizing line which together with said telegraph line interconnect said first and second stations and parallel each other, means connected to said lines to nullify the effect of extraneous voltages, a source of voltage connected to said neutralizing line, means responsive to a first predetermined signal at said second station to re-

move the voltage of said source from said neutralizing line to indicate to the operator at said first station that telegraph signals may be transmitted over said telegraph line, and means responsive to a second predetermined signal at said second station to apply said voltage to said neutralizing line to indicate to the operator at said first station that telegraph signals may not be transmitted over said telegraph line.

6. In a telegraph system, the combination of a first subscriber's station, a central office, a second subscriber's station connected to said central office, a line for telegraph signals, a neutralizing conductor which together with said line run substantially parallel to each other between the first subscriber's station and said central office, means connected to said line and said conductor for neutralizing extraneous voltages, an indicating device at said first subscriber's station controlled by voltage received over said neutralizing conductor from said central office, a source of voltage for connection to said neutralizing line, means responsive to a predetermined signal received at said central office from said second subscriber's station to effectively connect said first and second subscribers' stations through said central office so that telegraph signals may be transmitted between said stations over said line, said means also including means to remove the voltage of said source from said neutralizing conductor, and means responsive to a different predetermined signal received at the central office from said second subscriber's station to effectively disconnect said stations from each other and simultaneously apply said voltage to the neutralizing conductor to thereby operate said indicating device.

ROBERT JAMES EGNER.

CHARLES ROBERT WALKER.
